(57) **CLAIM**

The ornamental design for a charger for a shaver, as shown and described.

DESCRIPTION

FIG. 1 is a perspective view of a charger for a shaver;
FIG. 2 is a front view of the charger for a shaver of FIG. 1;
FIG. 3 is a rear view of the charger for a shaver of FIG. 1;
FIG. 4 is a first side view of the charger for a shaver of FIG. 1;
FIG. 5 is a second side view of the charger for a shaver of FIG. 1;
FIG. 6 is a top view of the charger for a shaver of FIG. 1;
and,
FIG. 7 is a bottom view of the charger for a shaver of FIG. 1.
The broken lines illustrate portions of the charger for a shaver that form no part of the claimed design.

1 Claim, 6 Drawing Sheets
